EDGE SETTING MACHINE

William Hamann, Irondequoit, N. Y., assignor to
 United Shoe Machinery Corporation, Borough
 of Flemington, N. J., a corporation of New
 Jersey

Application November 18, 1937, Serial No. 175,293

11 Claims. (Cl. 12—78)

This invention relates to finishing machines and is illustrated as embodied in a machine for burnishing or setting edges of soles.

In edge setting machines it is desirable to oscillate the setting tool at a very high speed. However, it is not possible to obtain as high a speed as is desired in the machines now available due to the excessive vibration of these machines when operated at a high speed. It is an object of this invention to reduce the mass of the moving parts in edge setting machines so as to reduce the vibration of these parts and thus enable the machine to operate at a higher speed. With this object in view, the heavy devices used in many prior machines for yieldingly resisting axial and rotative movement of the tool holders has been dispensed with and, in the illustrated machine, light springs located adjacent to the inner end of the tool holders have been substituted therefor.

In finishing machines in which the tool holder is rotatably mounted on an oscillating shaft so as to permit the operator to bring different tools on the tool holder into an operative position, a certain slight amount of clearance has to be provided between the tool holder and the shaft in order to permit the relative rotation of these members. After the machines have been in use for a time the clearance between the interfitting parts of the tool holder and shaft increases due to the wear on these parts resulting from their movement relatively to one another. It has been found that the relative movement of the tool holder and oscillating shaft which is permitted by the clearance between the interfitting parts of these members results in considerable vibration when they are oscillated at high speeds. Accordingly, it is a further object of this invention to eliminate this vibration by eliminating the clearance between the interfitting parts of the tool holder and the oscillating shaft when these members are in their operative positions. In the illustrated machine elimination of this clearance is accomplished by providing notched connections between the head and the shaft, the connections being so formed as to wedge the interfitting parts of the head and shaft into engagement with each other when these members are in their operative positions.

In edge setting machines wherein a tool head is axially and rotatably mounted on an oscillating shaft, resilient means are provided for yieldingly urging those members together so as to retain them in their operative position and yet allow them to be moved relatively to one another in

order that the head may be rotated to bring different tools into edge setting position. If the resilient means should break while the machine is oscillating at a high speed and thus allow the tool holder to fly out from the shaft, it would be likely to injure the operator as well as damage the machine. Accordingly, a feature of this invention lies in the provision of means for preventing an accidental separation of the head from the shaft. This means, as illustrated herein, consists of a retaining member which extends through the shaft and into engagement with the tool head, the engagement being such as to permit a limited axial movement of these members relative to one another, but positively prevent their separation.

With the above and other objects in view the invention will now be described with reference to the accompanying drawings and will be pointed out in the appended claims.

Fig. 1 is a perspective view of a portion of the head of an edge setting machine in which the present invention is embodied;

Fig. 2 is a plan view of the tool head and shifting fork shown in Fig. 3;

Fig. 3 is a side view partly in section of the tool head and its oscillating shaft;

Fig. 4 is a plan view of the head of the tool operating shaft;

Fig. 5 is a sectional view of the head shown in Fig. 4 taken along lines V—V;

Fig. 6 is a view illustrating the mounting means for the spiral springs shown in Fig. 3;

Fig. 7 is a sectional view taken along lines VII—VII of Fig. 3;

Fig. 8 is a sectional view taken along the lines VIII—VIII of Fig. 3;

Fig. 9 is a diagrammatic view, partly in section, showing the position of the tool head spindle as the lugs on the tool head enter the notches in the head of the operating shaft at the end of the tool head shifting operation, the clearance between the tool head parts and the operating shaft and the proportions of the lugs and notches being exaggerated for the purpose of illustration; and

Fig. 10 is a view similar to Fig. 9 showing the position of the tool head spindle when the lugs on the tool head are finally seated in the notches in the head of the operating shaft.

In setting shoe sole edges it is customary to use two edge setting irons, one for setting the sole edge around the forepart of the shoe and the other for setting the reduced edges in the shank portion of the sole. Accordingly, edge set-

ting machines are commonly equipped with tool heads carrying oppositely disposed edge setting irons. These heads are mounted on oscillating shafts and shifting mechanisms are provided for 5 successively shifting the tools into edge setting position. In the illustrated machine, the tool head 12 is provided with a pair of oppositely disposed burnishing tools 10, and is adjustably mounted on an oscillating shaft 25. Mounted 10 adjacent to the tool head 12 is a cooperating shifting fork 32 for shifting the burnishing tools successively into edge setting position. The tool head shifting mechanism disclosed herein is well known in the art and is fully described in Letters 15 Patent of the United States No. 1,986,968, granted January 8, 1935, upon an application filed in the name of W. Hamann, to which reference may be had for a detailed description of this mechanism.

The burnishing tools 10 are attached to tool 20 retaining spindles 11 which are slidably and rotatably mounted in oppositely extending recesses in the tool holder 12. The inner ends of these spindles are slotted to receive portions of flat springs 14, the ends of which engage 25 shoulders 13, formed on the tool holder 12 at either side of the spindle receiving recesses. The springs are retained in the slots in the spindles by set screws 39 (Fig. 3) which are located at the inner end of the spindles and extend into 30 clamping engagement with the springs. These springs permit a limited rotation of the spindles in the recesses in the tool holder so as to permit the tools carried by the spindles to follow the changes in curvature of sole edges. Upon 35 the disengagement of the sole edges from the tools, the springs return the tools to their normal sole edge engaging positions. The tool carrying spindles are yieldingly urged outwardly by balls 16 (Fig. 2) seated in recesses in the inner 40 ends of the spindles. These balls are bored to receive the inner ends of springs 18 coiled about studs 17 fixed to the shoulders 13 on the tool head. The outer ends of the springs 18 are hooked about pins 19 (Fig. 6) carried by washers 20 which are adjustably mounted on the 45 studs 17 the washers 20 being above the springs 18. The upper faces of these washers are serrated so as to cooperate with the opposed serrated faces on adjoining washers 21 (Fig. 6) 50 which are non-rotatably mounted on the studs 17. The washers 20 are also provided with recesses 39 for the reception of an appropriate adjusting tool. The springs and washers are held in assembled relation on the studs by nuts 22, 55 threaded on the ends of the studs 17. The force exerted by each spring 18 on its tool retaining spindle may be varied by the operator by adjusting the tension in the spring by rotating the washer 20, the washer being retained in any 60 adjusted position by the locking washer 21. As is evident from the disclosure in Fig. 1, the adjustable washers 20 are located on the tool head in such a manner as to be readily accessible to the operator so as to permit him to vary the pressure on the spindles to suit the type of soles he is operating upon.

The tool head 12 is provided with a pair of oppositely disposed depending lugs 27, 27' which are received in a pair of notches 36, 37 formed 70 in the side walls of a cup-shaped head 26 on the oscillating shaft 25, thus providing a positive driving connection for the transmission of oscillating movement from the shaft 25 to the tool head. The tool head is also provided with 75 a hollow axially disposed depending spindle 23

which is slidably and rotatably received in an opening 24 in the oscillating shaft 25. Mounted in the opening in the shaft 25 between the side walls of the shaft and the spindle 23 is a bearing sleeve 28 which extends beyond the spindle 5 23 and is provided with a roller bearing 40 at its inner end. The tool head is urged into engagement with the head 26 of the oscillating shaft by a spring 38 which extends through the opening in the spindle 23 (Fig. 3), and is connected at one end by a member 29 to the bearing 40 in the sleeve 28, and at the other end to the tool holder by a member 43 which engages a U-shaped washer 31 seated on the head. This spring permits the shifting fork 32 to move 10 the tool holder outwardly from the drive shaft until the lugs 27 have cleared the side walls of the notches 36, 37 and are moved on to the inclined shoulders 38 on the head of the operating shaft so as to permit the shifting of the 20 tool head to bring another tool into edge setting position. Provision is made for preventing the separation of the tool head from the oscillating shaft in the event of breakage of the spring 38. This consists in the provision of a peripheral 25 groove 33 (Fig. 3) in the tool head spindle 23 which receives a locking pin 34. The locking pin 34 extends through the side walls of the shaft 25 and bearing sleeve 28 and is retained in engagement with the groove in the spindle by a 30 split spring 35 which surrounds the shaft 25. The width of the peripheral groove in the spindle is greater than the depth of the notches in the head 26, thus permitting the spindle to be moved outwardly from the drive shaft sufficiently 35 for the lugs 27 to clear the notches 36, 37 in the side walls so as to permit the head to be rotated in order to shift the burnishing tools. Further movement of the spindle is prevented by the engagement of the pin 34 with the lower 40 end wall of the peripheral groove 33.

In order to permit free axial and rotative movement of the spindle 23 in the sleeve 28 clearance must be allowed between these members. After the machine has been operated for a time, this 45 clearance is increased by wear on the spindle and sleeve due to the frequent shifting of the tool head. The clearance between the spindle and sleeve has been found to be the cause of considerable vibration in the tool head and shaft when the tool head and shaft are oscillated at high speeds. To eliminate the effect of this 50 clearance and thus reduce the vibration of the machine during edge setting operations and thereby allow the edge setting tool to be operated at higher speeds, the connections between the head of the drive shaft and the lugs on the tool head have been so formed that movement of these members toward one another under the influence of the spring 38 will cause the 55 tool head to move laterally with respect to the shaft 25 thereby moving the tool head spindle 23 into wedging engagement with the bearing sleeve 28 on that shaft. These connections consist of oppositely disposed depending lugs 27, 27' on 60 the tool head 12 which are provided with inclined edge portions 44, best shown in Figs. 7 and 8. These lugs 27, 27' are received in the notches 36, 37 in the shaft head 26 which are wider than the lugs 27, 27' so that only one 65 side of the lug engages a side wall of the notch into which it is received. The side walls of the notch 36 are straight while the lug engaging side wall 44 of the notch 37 is inclined or wedge shaped, as is shown in Fig. 4. The effect 70

of this arrangement can best be understood by referring to Figs. 9 and 10 which are diagrammatic views on an exaggerated scale illustrating the relative positions of the tool head lugs, tool head spindle and operating shaft as (Fig. 9) the lugs enter the notches in the head of the operating shaft and when (Fig. 10) the lugs are finally seated in the notches. As the lugs 27, 27' on the tool head first enter the notches 36, 37 at the end of a shifting operation (Fig. 9), the spindle 23 is substantially concentric with the sleeve 28 and there is a clearance C extending completely around the spindle 23. After the lugs have entered the notches 36, 37 the inclined edge portion 44 of the lug in the notch 37 will ride down on the inclined surface 41 (Figs. 8 and 10) under the urging of the spring 30 thus causing a further movement of the lugs into the notches. This movement will continue until the tool head has reached the position shown in Fig. 10 where the lug 27' in the notch 36 engages the face 42 of that notch at X and the spindle 23 is pressed against the sleeve 28 at Y. The spindle 23 will be held pressed against the sleeve 28 throughout the edge setting operation by the spring 30 which continually urges the lug in the notch 37 downwardly on the inclined side wall 41 thereby wedging the spindle 23 against the sleeve 28. When the lugs 27, 27' are finally seated in the notches 36, 37 there remains a clearance between the lugs and one wall of the notches which is indicated by the letters D and E in Fig. 10. This clearance permits the lug in the notch 37 to ride further downward on the inclined wall 41 (Fig. 8) as wear develops in the spindle 23 and sleeve 38 and thus provides for their continued wedging engagement during the period when they are in their operative positions.

40 The shaft 25 is rotatably mounted in a bearing 45 supported by a machine frame 46, and may be oscillated by any suitable means such, for example, as that illustrated in Letters Patent of the United States No. 1,743,480, granted January 14, 45 1930, in the name of E. J. Ray.

When it is desired to change tools, the tool holder, as viewed in Fig. 3, is moved outwardly from the shaft by the shifting fork 32 until the lugs 27 engage the shoulders 38 on the head of the oscillating shaft after which it is automatically rotated to shift the tools in a manner fully described in the above-mentioned patent to Hamann No. 1,986,968.

Having described my invention, what I claim as new and desire to secure by Letters Patent of the United States is:

1. In a finishing machine, an oscillating tool holder having a recessed head, a tool retaining spindle mounted for rotative movement in the recess in said head, and a spring extending transversely to the longitudinal axis of the spindle, said spring having an intermediate portion thereof positively connected to the tool spindle and its end portions engaging adjacent sections of said head whereby rotation of said spindle is resisted by said spring.

2. In a finishing machine, an oscillating tool holder having a recessed head and abutments adjacent to the recess in the head, an apertured tool retaining spindle mounted for rotative movement in the recess in said head, and a spring engaging said abutments and extending into the aperture in the tool retaining spindle for resisting rotation of the spindle and for limiting the extent of such rotation.

3. In a finishing machine, an oscillating tool holder having a recessed head, a tool retaining spindle mounted for axial movement in the recess in said head, a post offset from the axis of said spindle, a spiral spring mounted on said post, 5 said spring having an extending portion arranged for engagement with the spindle, and means for adjustably connecting the spring to the post whereby the force exerted by the spring on the spindle may be varied.

4. In a finishing machine, an oscillating tool holder having a recessed head and a spring support, said spring support being located to one side of the recess, a tool retaining spindle mounted for axial movement in the recess in said head, a 15 spring arranged to urge the spindle outwardly in said recess, and means for adjustably connecting the spring to the spring support whereby the force exerted by the spring on the spindle may be varied.

5. In a finishing machine, a tool holder having a recessed head, a slotted tool retaining spindle mounted for axial and rotative movement in said recess, a spring extending through the slot in said spindle and having its ends in engagement 25 with adjoining portions of the head thereby to resist rotation of the spindle in the recess and a spiral spring mounted on said head with its axis offset from the axis of said spindle, said spring having an offset portion arranged to urge said 30 spindle outwardly from said head.

6. In a finishing machine, a recessed oscillating shaft, a tool holder mounted for axial and rotative movement in the recess in said shaft, resilient means for resisting axial movement of said 35 shaft and said holder relative to one another, and means for limiting the extent of the relative axial movement of the shaft and the holder in the event of breakage of said resilient means.

7. In a finishing machine, an oscillating shaft, 40 a tool holder mounted for axial and rotative movement on said shaft, and connections between said holder and said shaft constructed and arranged to move them into wedging engagement with one another to prevent vibrations of said holder relatively to said shaft.

8. In a finishing machine, a recessed oscillating shaft, a tool holder mounted for axial and rotative movement on said shaft, said tool holder including a shank extending into the recess in said shaft, and connections between said tool holder and said shaft constructed and arranged to press said shank against a portion of said shaft thereby to prevent vibration of the shank in the recess.

9. In a finishing machine, an oscillating shaft, 55 a holder for a plurality of tools mounted for rotation on the shaft whereby they may be successively brought into operative position, means for releasably locking the holder to the shaft comprising connections therebetween, said connections being constructed and arranged to displace said holder relatively to the shaft a distance equal to the clearance between them to cause them positively to engage one another thereby to eliminate vibration between the shaft and holder when they are oscillated in their locked relation.

10. In a finishing machine, a recessed oscillating shaft, a holder for a plurality of tools rotatably mounted on said shaft whereby the tools 70 may be successively brought into operative position, said holder including a shank extending into the recess in said shaft, means for releasably locking the shaft to the holder in its different operative positions, said means comprising notched 75

connections between the holder and the shaft, said connections being constructed and arranged to move the spindle into wedging engagement with the shaft thereby to eliminate vibration between them when oscillated in their locked position.

5. 11. In a finishing machine, a recessed oscillating shaft, a holder for a plurality of tools rotatably mounted on said shaft whereby the tools may be successively brought into operative position, said holder including a shank extending into the recess in said shaft, means for releasably locking

the shaft to the holder in its different operative positions, said means comprising extensions on said holder and recesses on said shaft arranged to receive said extensions, said recesses being wider than said extensions and one of said recesses being provided with an inclined surface arranged for engagement with the extension entering that recess whereby the extension entering that recess is moved an additional distance thereby moving the holder relatively to the shaft and forcing the spindle into engagement with the shaft.

10 WILLIAM HAMANN.
